US0D1020537S

(12) **United States Design Patent** (10) Patent No.: **US D1,020,537 S**
Chung (45) Date of Patent: ** Apr. 2, 2024

(54) **MOTOR VEHICLE, TOY VEHICLE REPLICA AND/OR OTHER REPLICA**

(71) Applicant: **Dr. Ing. h.c. F. Porsche Aktiengesellschaft**, Stuttgart (DE)

(72) Inventor: **Woosung Chung**, Stuttgart (DE)

(73) Assignee: **Dr. Ing. h.c. F. Porsche Aktiengesellschaft** (DE)

(**) Term: **15 Years**

(21) Appl. No.: **29/780,829**

(22) Filed: **Apr. 27, 2021**

(30) **Foreign Application Priority Data**

Oct. 28, 2020 (EM) 8216121-0001

(51) LOC (14) Cl. **12-08**

(52) U.S. Cl.

USPC **D12/91**

(57) **CLAIM**

The ornamental design for a motor vehicle, toy vehicle replica and/or other replica, as shown and described.

DESCRIPTION

FIG. 1 is a perspective view of a motor vehicle, toy vehicle replica and/or other replica;

FIG. 2 is a front view thereof;

FIG. 3 is a rear view thereof;

FIG. 4 is a right side view thereof, the left side being a mirror image of the right side; and,

FIG. 5 is a top plan view thereof.

The broken line showing of the motor vehicle, toy vehicle replica and/or other replica forms no part of the claimed design.

1 Claim, 5 Drawing Sheets
